UNITED STATES PATENT OFFICE

2,466,213

METAL PROTECTOR FOR HORSE COLLARS

David E. Davis, Walters, Okla.

Application June 27, 1947, Serial No. 757,389

1 Claim. (Cl. 54—19)

1

This invention relates to a reinforcing device for horse collars, and has as its primary object the provision of means for increasing the strength of horse collars at the point of maximum drag, and consequently prolonging the life of such collars.

An additional object of the invention is the provision of a metallic reinforcing strip adapted to be applied to horse collars, and so arranged and constructed as to preclude the metal touching the body of the animal.

An additional object of the invention is the provision of such a device having means associated therewith whereby the collar may be readily separated when desired.

Still others will in part be obvious, and in part be pointed out as the description of the invention proceeds, and shown in the accompanying drawing wherein there is disclosed a preferred embodiment of this inventive concept.

In the drawing:

Figure 1 is a front elevational view of one form of collar embodying features of the instant invention.

Figure 2 is an exploded perspective view disclosing the reinforcing attachment as separated from a collar, and

Figure 3 is a sectional view taken substantially along the line of 3—3 of Figure 1.

Similar reference characters refer to similar parts throughout the several views of the drawing.

Referring now to the drawings in detail, and more particularly to Figure 1, there is generally indicated at 10 a horse collar, of substantially conventional design, including an inner rim 11 adapted to bear against the neck of an animal, and comprised of a leather coating or the like filled with padding material 12 (see Figure 3). The horse collar is also comprised of an outer flanged portion 13 which may be integral with the portion 11, and separated therefrom as by a line of stitching 14 or the like, the exterior of the device being stitched together to form a flange 15.

The device is separable at its upper half, and includes a buckle 16 and strap tongue 17 for securing the parts in related assembly.

The lower portion is also separable, and this point, generally designated at 20 comprises one of the points of greatest wear on normal horse collars. The other two points on the side of the device generally indicated at 21 comprise the points of maximum draw by the traces of the animal, and are consequently subject to greater wear than other portions of the device.

2

The reinforcing member of the instant invention, as best shown in Figure 2, comprises two separate metallic strips, 23 and 23¹, each of which is provided with a relatively wide portion 24 and 24¹ respectively terminating at its outer edge in a flange 25 and 25¹ provided with rivet holes 26 and 26¹. The flanges 24 and 24¹ are adapted to be positioned adjacent the points 21, as best shown in Figure 1, and secured in position as by rivets 27 (see Figure 3) passing through the flange 15, and so arranged as not to interfere with the draw straps, or engage the body of the animal. The inner edges of strips 23 and 23¹ are upturned to provide a second flange 123 and 123¹ provided with rivet holes 28. Rivets 128 enter through these holes as well as two thicknesses of leather as seen in Figure 3. Both strip 23 and 23¹ include extending tongues 29 and 29¹, adapted to extend to a point adjacent the extreme bottom of the horse collar. The tongue 29 is provided with a plate 30, having two extending projections 31 thereon interiorly apertured to provide a bolt hole, while the tongue 29¹ is provided with a corresponding plate 32, having three projections 33 thereon, forming corresponding tongues adapted to interengage with the tongues 31. A bolt 34 is provided adapted to pass through the aligned apertures of the portions 30 and 32, and is provided with an aperture 35 at one end adapted for the engagement of a cotter pin 36 to hold the parts in related assembly.

As best shown in Figure 1 portions 30 and 32 may be secured to the extremities of the collar member as by means of rivets 37 or the like.

In order to preclude the contact of metal portions 30 and 32 with the neck of the animal a relatively soft leather flap 40 is provided, adapted to be suitably secured as by tacks or rivets 41 to the collar adjacent the clasp formed by plates 30 and 32, and 34, one end thereof being free, to permit ready disengagement of the parts, and the device being of sufficient size to cover all the metal parts.

From the foregoing it will now be seen that there is herein provided an improved collar reinforcing member which protects the points of greatest wear on a conventional horse collar, which permits ready separation of the lower halves of the device, and which consequently prolongs the durability and life of the device, thus accomplishing all the objects of this invention, and others, including many advantages of great practical utility and commercial importance.

As many embodiments may be made of this inventive concept, and as many modifications

may be made in the embodiment hereinbefore shown and described, it is to be understood that all matter herein is to be interpreted merely as illustrative and not in a limiting sense.

I claim:

In a reinforcing device for horse collars, a pair of metal strips adapted to be secured to opposite sides of the collar, coacting plates at the extremities of said strips having aligned apertures therein, and a pin adapted to be passed through said apertures for holding said strips together, said strips being provided with widened portions at the points of greatest wear on the collar and flanges at the outer extremities of said widened portion for engaging said collar for receiving means for fixing said portion to said collar. **15**
